TROLLEY CONVEYER

Toku Uyehara, Paauilo, Territory of Hawaii

Application March 29, 1938, Serial No. 198,768

2 Claims. (Cl. 214—86)

This invention relates to trolley conveyers and has for an object to provide a trolley conveyer designed more particularly for conveying bundles of sugar cane from a cane field to a flume or other 5 conveyance for transportation to a sugar mill.

A further object is to provide apparatus of this character which will be portable and may be moved longitudinally of the flume as the harvested bundles of cane are picked up in the field. 10 A further object is to provide apparatus of this character in which the aerial forks will automatically open when reaching a predetermined position at the flume.

A further object is to provide an apparatus of 15 this type in which the aerial forks will be gravity operated in both their loaded and their empty conditions.

With the above and other objects in view the invention consists of certain novel details of construction and combinations of parts hereinafter 20 fully described and claimed, it being understood that various modifications may be resorted to within the scope of the appended claims without departing from the spirit of sacrificing any of 25 the advantages of the invention.

In the accompanying drawings forming part of this specification,

Figure 1 is a side elevation of a trolley conveyer constructed in accordance with the invention, the central portions of the cables being broken away.

Figure 2 is a plan view of the apparatus shown in Figure 1.

Figure 3 is a longitudinal sectional view of 35 the wheeled cable support at the unloading end of the apparatus taken on the line 3—3 of Figure 1 with parts in elevation.

Figure 4 is a side elevation of the wheeled cable support at the loading end of the apparatus.

40 Figure 5 is a fragmentary side elevation, partly in section, of one of the tubular tracks for the cables and showing trolley wheels of the aerial forks.

Figure 6 is a fragmentary side elevation of the 45 jointed tubular track which lifts empty aerial forks to a respective cable to be returned to loading position.

Figure 7 is a cross sectional view taken on the line 7—7 of Figure 6 and showing one of the 50 trolley wheels applied to the tubular track.

Figure 8 is a fragmentary side elevation showing the reversed side of the hinged track shown in Figure 6.

55 Figure 9 is an end elevation of one of the trolley wheels and showing the removable pin for

locking the wheel stationary on the respective cable while the aerial fork is being elevated from loading position to traveling position.

Figure 10 is a side elevation of one of the aerial forks with parts in section. 5

Figure 11 is a front elevation of one of the aerial forks with parts broken away.

Figure 12 is a detail longitudinal sectional view showing the aerial fork locking pin in operative position to hold the fork closed upon a bundle of 10 cane.

Figure 13 is a detail sectional view of the parts shown in Figure 12 but showing the locking pin in position to permit the aerial fork to dump the load. 15

Referring now to the drawings in which like characters of reference designate similar parts in the various views, 10 designates a platform which is supported upon ground wheels 11 to be maneuvered by a tractor 12 or other means 20 of transportation to the end that the platform may be located at desired points longitudinally of a flume 13 or other device to be loaded for transporting harvested cane from a cane field 25 to a mill, or railway car.

Rising from the wheeled platform are a plurality of posts 14. An inclined chute 15 is mounted for vertical adjustment on the post by collars 16 and set screws 17. The chute is provided at the bottom edge with a hinged apron 18 which 30 is adapted to direct material from the chute to the flume.

Preferably three tubular tracks 19, 20 and 21 are supported by transverse bars 22 at the upper ends of the posts and by inclined braces 23 which 35 rise from the platform, as best shown in Figures 1, 2 and 3. As best shown in Figure 7 each track is formed of substantially tubular sheet metal slit longitudinally to permit the bracket arms of hereinafter described trolley wheels to pass longitudinally through the track. The material on one side of the slit is directed upwardly and provided with a bead 24 which forms a rail for the trolley wheel 25 of an aerial fork 26 later described. 40

The tubular tracks at the front portions thereof extend substantially horizontal and are directed downwardly at the rear portions, as best shown in Figure 1. The intermediate tubular track 20 has the rear portion thereof hinged as 50 shown at 27 to the horizontal front portion so that it may be rocked upward to the horizontal by a block and tackle 28.

Each tubular track is provided with a respective cable upon which the aerial forks travel, the 55

cables being designated by the numerals 29, 30 and 31. These cables are connected to the rails 24 at the front end thereof and as best shown in Figure 5 the connection may be formed through the instrumentality of a sleeve 32 on the cable screw threadedly engaged with a reduced extension 33 of the track.

The aerial forks after entering the tubular tracks at the front ends thereof are automatically dumped on to the chute 15 and continue travel down the sloped rear ends of the tubular tracks until discharged on to the ground. Thereupon the aerial fork may be retrieved and placed upon a hook 34 which extends from the rear end 15 of the rail of the intermediate tubular track 20.

By operating the block and tackle 28 the pivoted rear end of the tubular track 20 may be elevated to a position which inclines downwardly from the horizontal thus giving the aerial fork a start on its journey down the respective cable 30 to the location on the field where it is to be loaded.

At the loading location a switch 35, best shown in Figures 1 and 2, deflects the gravitating aerial fork from its cable on to the ground. It may then be retrieved and placed on one of the outermost cables 29 and 31 for loading ready to begin its return journey to the delivery chute 15.

Each aerial fork comprises a plurality of 30 curved tines 36 connected by cross bars 37, as best shown in Figures 10 and 11. A curved latch bar 38 is pivotally connected at the bottom to one of the cross bars 37. The latch bar embraces the bundle 40 of cane. The bundle is held in 35 the fork through the instrumentality of a chain 41 which is yieldably connected to an eye 42 on the latch bar by a helical spring 43. A link of the chain is hooked over a projecting tongue 44 formed on a tube 45 which is welded to one 40 of the cross bars 37 and is fixed by a post 39 to another of the cross bars 37, as best shown in Figures 12 and 13. The spring 43 holds the link of the chain tightly in place on the tongue 44.

45 A trip rod 46 is slidably mounted in the tube 45 and at the rear end is provided with a curved trigger 47. At the front end the rod is provided with a collar 48 having a slot 49 therein to receive the tongue 44 of the tube.

50 When a loaded fork arrives at the chute 15 the trigger 47 of the rod impinges against a U-shaped abutment 50 disposed on the rear end of the chute whereupon the rod 46 is thrust forward and the collar 48 thereof dislodges the chain from the tongue 44. At the same time a spring 51, connected to the eye 42 of the latch bar and to one of the cross bars 37 of the fork, contracts and swings the latch bar to open position. The bundle of cane gravitates from the 55 open fork on to the chute 15 and is delivered by the apron 18 into the flume 13.

60 By again referring to Figure 3 it will be seen that a pair of U-shaped arms 52 are disposed at the upper end of the chute. The arms contact with the rear side of the ends of the bundle 40 of cane at the same time the trigger of the aerial fork is tripped by the abutment 50 so that during continued rearward travel of the aerial fork the bundle of cane will be thrust forcibly 65 out of the open fork.

65 At the loading position of the aerial forks the cables are supported by posts 53 which rise from a platform 54 supported upon wheels 55 and adapted to be maneuvered by a tractor 56. The 70 posts are of such height that the cables 29 and

75 31 for loaded aerial forks will slope downwardly toward the tubular tracks and facilitate the forks traveling along the cables to the tracks by gravity. The cables 29 and 31 are trained over pulleys 57 arranged at the upper ends of the posts and thence downwardly along the posts passing over pulleys 58 at the bottom of the posts to windlasses 59 disposed on the platform 54 and controlled by clutches 60 to be driven from the motor of the tractor 56.

10 The cable 30 upon which empty aerial forks return to loading position is trained over a pulley 61 disposed on the centermost post 53 near the bottom thereof and from thence is trained upwardly along the post and over a pulley 62 and 15 from thence is trained downwardly to a windlass 63 disposed on the post and operated by a crank handle 64. The lowermost pulley 61 is mounted in a bearing 65 which is adjustably mounted in a guide slot 66 formed in the post to vary the slope 20 of the cable 30.

The cables may all be unwound from their respective windlasses or wound up thereon to accommodate various loading positions of the aerial forks with respect to the delivery position. Moreover, the cables 29 and 31 are adapted to be unwound from their respective windlasses to permit a sufficient slack on the cable to lower a fork to ground level, as best shown in Figure 1, so that a bundle of cane may be scooped up 30 and loaded in the fork through the instrumentality of the heretofore mentioned chain 41 and a cord 67 attached to the end of the chain.

25 By referring to Figures 5 and 9 it will be seen that the trolley wheel 25 is provided with a 35 plurality of openings 68 which pass through both flanges of the trolley wheel. A pin 69 is selectively passed through a pair of these openings to clamp the trolley wheel stationary upon either cable 29 or 31 while the slack is being taken up on the cable to elevate the respective aerial fork when loaded upon the ground, to a sufficient height so that it will slope downwardly to promote gravitation of the loaded fork to the receiving chute 15. Thereupon the pin is withdrawn 40 through the instrumentality of a cord 70 to permit the trolley wheel to travel to the unloading position.

45 While the invention has been described in connection with the conveyance of harvested cane 50 stalks it is obvious that the conveyance of other materials may be equally well accomplished where mobility or portability at the receiving and discharge ends as well as variations of the distances between the receiving and discharge ends 55 of the apparatus is desirable.

55 From the above description it is thought that the construction and operation of the invention will be fully understood without further explanation.

60 What is claimed is:

1. A trolley conveyer comprising a plurality of cables, portable supports for the ends of the cables permitting the trolley conveyer being moved bodily along the field while engaged in harvesting or other work, a track on one of the supports connected to a respective one of the cables and having a downwardly extending rear end, a track on the last named support connected to another one of the cables and having a hinged rear end 70 terminating in a hook, aerial forks for collecting bundles of grain or other material having trolley wheels engageable with said cables, the downwardly directed rear end of one of the tracks permitting of an aerial fork gravitating to the 75

ground to be retrieved and placed on the fork of the hinged rear end of the other track, means for elevating said hinged end with an empty fork thereon for return to the respective cable for transportation to the field to be loaded, a chute disposed below said tracks, and means on the chute for operating a loaded aerial fork to deposit its load on the chute.

2. A trolley conveyer comprising a plurality of cables, portable supports for the ends of the cables permitting the trolley conveyer being moved bodily along the field while engaged in harvesting or other work, a track on one of the supports connected to a respective one of the cables and having a downwardly extending rear end, a track on the last named support connected to another one of the cables and having a hinged rear end terminating in a hook, aerial forks for collecting bundles of grain or other material having trolley

wheels engageable with said cables, the downwardly directed rear end of one of the tracks permitting of an aerial fork gravitating to the ground to be retrieved and placed on the fork of the hinged rear end of the other track, means for elevating said hinged end with an empty fork thereon for return to the respective cable for transportation to the field to be loaded, a chute disposed below said tracks, means on the chute for operating a loaded aerial fork to deposit its load on the chute, means on the other portable support adapted to wind up and pay off said cables to accommodate changes of distances between both portable supports, and means for slackening off one of the cables to receive a loaded aerial fork preparatory to elevating the fork for its journey by gravitation to the chute on its respective cable. 5 10 15
